UNITED STATES PATENT OFFICE.

PHILLIP PHANEUFF AND HARRY GERHARD, OF DETROIT, MICHIGAN.

HAT-FASTENER.

1,176,241.

Specification of Letters Patent.

Patented Mar. 21, 1916.

Application filed August 13, 1915. Serial No. 45,307.

To all whom it may concern:

Be it known that we, PHILLIP PHANEUFF and HARRY GERHARD, citizens of the United States of America, residing at Detroit, in the county of Wayne and State of Michigan, have invented certain new and useful Improvements in Hat-Fasteners, of which the following is a specification, reference being had therein to the accompanying drawings.

This invention relates to a hat and hair holding device, and the primary object of our invention is to provide a hat with positive and reliable means, in a manner herein- 15 after set forth, for retaining the hat on the head of a wearer without using ordinary hat pins, which are injurious to a hat and hair, besides being dangerous when the pointed ends thereof protrude from the 20 crown of the hat.

Another object of our invention is to furnish a hat with detachable holding means which can be easily and quickly adjusted to engage in and hold the hair at any 25 desired point, the means employed being practically invisible and such portions as are exposed being ornamental and neat in appearance.

A further object of our invention is to 30 provide a hat and hair holding device wherein the parts are constructed with a view of reducing the cost of manufacture and at the same time retain the features by which safety, durability, simplicity and 35 ease of assembling are secured, and with such ends in view, our invention resides in the novel construction and arrangement of parts to be hereinafter specifically described and then claimed.

40 Reference will now be had to the drawing, wherein—

Figure 1 is a front elevation of the device in a hat; Fig. 2 is a perspective view 45 of a portion of the device showing a comb in a raised position; Fig. 3 is a similar view 50 of the device showing the comb in a lowered position; Fig. 4 is an enlarged vertical sectional view of a portion of the device with a comb in a raised position, and Fig. 5 is a 55 sectional view of a portion of the device showing a portion of the comb in a lowered position.

In the drawing, 1 denotes a flexible band or strip having one end thereof provided 55 with a guide 2 and a stud 3, while the opposite end is apertured, as at 4, whereby after

the apertured end is placed in the guide 2, one of the apertures 4 will receive the stud 3 and thereby form a band that may be easily and quickly adjusted to fit within the 60 crown 5 of a hat and on the head of a wearer.

Slidable on the band 1 are holders 6 having the upper ends thereof pronged, as at 7 and the lower ends formed with loops 8. 65 The prongs 7 of the holders 6 are adapted to engage in the crown 5 of the hat, as shown in Figs. 1 and 4, and prevent accidental displacement of the hat relative to said holders. The holders 6 have enlarged 70 slotted portions 9 providing clearance for the band 1 and said holders can be easily shifted to engage the inner wall of the hat crown at any desired point.

Detachably suspended from the looped 75 ends of the holders 6 are combs 10 having tines that are slightly bowed and adapted to enter the hair of the wearer when raised and pushed in the hair. Each comb has a central tine 11 provided with a pear shaped 80 head 12 by which the comb is suspended from its holder. The head 12 is substantially flat in side elevation, as shown in Fig. 4 and can be placed in the looped end 8 of the holder and turned a quarter of a revolution whereby the comb will be suspended 85 from the holder. The tine 11 loosely fits in the looped end of a holder, and in consequence of this arrangement, the comb can be pushed upwardly to assume the position 90 shown in Figs. 1 and 2 and all of the tines will coöperate in preventing accidental displacement of the device and the hat. Each comb may have an ornamental head, as 95 shown in Fig. 2, or a hair holding head as shown in Fig. 3, such a head clamping the hair against the forehead to hold it as arranged. In either instance, the head of the comb has a pocket 13 and prongs 14. The pockets 13 are adapted to receive the lower 100 looped ends 8 of the holders 6, and the prongs 14 are adapted to engage in the crown of the hat, as shown in Figs. 1 and 4. When the comb is raised the head of the same renders the lower end of the holder 105 invisible and by manipulating the comb or the hat, the prongs 14 can be easily placed in engagement with the hat, to coöperate with the prongs 7 of the holders in anchoring the device relative to the hat, while the 110 combs at each side of the head coöperate in retaining the device on the head and the

hair as previously arranged. With some styles of hats the entire device is invisible while with sailor hats or those having upturned brims, only the heads of the combs 5 are exposed.

The flexible band can be made of whale bone or any flexible material, and the holders and combs may be made of celluloid, bone or any material that may be ornate 10 ment and present a neat and attractive appearance.

One embodiment of our invention has been illustrated but it is to be understood that the structural elements are susceptible 15 to such variations and modifications, as fall within the scope of the appended claims.

What we claim is:—

1. The combination with a hat, of a band adapted to fit therein, holders on said band 20 having prongs adapted to engage in said hat, and combs suspended from said holders and having prongs adapted to engage in said hat when said combs are elevated.
2. The combination with a hat, of a band 25 adapted to fit therein, holders slideable on

said band provided with prongs adapted to engage in said hat, combs detachably suspended from said holders and provided with pockets adapted to receive the lower ends of said holders, and prongs on said 30 combs adapted to engage in said hat and coöperate with the prongs of said holders in preventing accidental displacement of said band.

3. The combination with a hat, of adjustable 35 holders adapted to engage in the crown of said hat, combs detachably suspended from said holders and provided with pockets adapted to receive the ends of said holders, and prongs forming part 40 of said combs and adapted to engage in said hat.

In testimony whereof we affix our signatures in presence of two witnesses.

PHILLIP PHANEUFF.
HARRY GERHARD.
